UNITED STATES PATENT OFFICE.

JOHN A. LINN, OF SIOUX CITY, IOWA, ASSIGNOR OF THREE-FIFTHS TO BUEL COUCH,
OF SIOUX CITY, IOWA.

CAN OPENER.

Application filed December 11, 1922. Serial No. 606,024.

To all whom it may concern:

Be it known that I, JOHN A. LINN, a citizen of the United States, and a resident of Sioux City, in the county of Woodbury and State of Iowa, have invented certain new and useful Improvements in Can Openers, of which the following is a specification.

My invention has for its object the production of a can-opener embodying certain novel features of construction and arrangements of parts whereby the head of the can is sheared closely adjacent the rim and leaves no burrs or rough edges whatever.

Another object of the invention is the production of a device of this class which opens a can quickly with little effort on the part of the operator, and which is comparatively inexpensive in production.

The above objects I successfully attain in a device consisting, broadly, of two handles pivoted together scissors-like, one having a shoulder engaging the under edge of the rim and adjacent the periphery of the can, and the other having a blade which shears downwardly through the head of the can and adjacent the rim, all of which will be clearly understood from the following detailed description, reference being had to the accompanying drawings which form a part of this specification and in which like characters of reference indicate corresponding parts throughout the several views, of which,—

Fig. 1 is a side elevation of a can-opener embodying my invention:

Fig. 2 is a plan of the upper handle and its jaw.

Fig. 3 is an inverted plan of the lower handle and its jaw.

Fig. 4 is a front elevation of the device as applied to a can, and

Fig. 5 is a similar view in the act of shearing the head of a can, a part being cut away.

Referring, now, to the illustrations, I provide upper and lower handles, 6 and 7, respectively, pivoted together, as at 8, the upper handle carrying the lower jaw, 9, and the lower handle provided with the upper jaw, 10. The jaws are laterally offset in like directions, as at 11, in order that the handles and the hand of the operator will be out of the way of the can in operation. The lower jaw, 9, is provided with a suitable upper projection or shoulder which may be afforded by the plate, 12, engageable adjacent the periphery of the can with the under edge

of the bead, 13, of the can, 14 (Figs. 4 and 5). The lower edge of the jaw, 9, is provided with a lateral projection engageable with the periphery of the can to hold the plate, 12, at a slight angle to the wall of the can, as clearly shown in Figs. 4 and 5. This may be afforded by a narrow flange, 15, on the lower edge of the plate, 12.

The upper edge of the plate, 12, is preferably curved longitudinally, as at 16, to permit the plate to roll on the under edge of the bead of the can, when the device is operated, as will presently appear. The forward end of the jaw, 9, also is preferably provided with a hook, 17, engageable over the rim of the can to facilitate operation and prevent accidental displacement of the device as it travels around the can.

The upper jaw, 10, carries a suitable blade, 18, the under edge of which is beveled to a sharp edge on the side thereof remote from the plate, 12, the said blade being so positioned and related to the plate, 12, that it will shear through the head of the can closely adjacent the rim. The blade, 18, is also curved slightly longitudinally to conform, somewhat, to the curvature of the wall of the can.

The plate, 12, being disposed at a slight angle to the wall of the can and the blade, 18, prevents binding of the wall of the can between the plate and blade.

The jaws are preferably held yieldably open by a leaf spring, 19, between the handles.

It is thought the operation of the device is readily apparent, and that it completely shears the head from the can, with little effort on the part of the operator, and leaves a smooth edge which does not project inside of the can to injure a person's hands or in the least obstruct the removal of the contents of the can.

While I have illustrated and described but one embodiment of the invention, I would not be understood as being limited to the specific structure disclosed, for numerous alterations and modifications in the details of construction and arrangement of parts, may be made without departing from the spirit and scope of the invention, as defined by the following claims, to-wit:

1. An opener for a can having a bead, comprising upper and lower jaws movable toward and from each other, the lower jaw

including a plate engageable with the under edge of the bead, and a lateral projection engageable with the wall of the can to hold said plate at a slight angle thereto, a blade 5 on the other jaw to shear through the head of the can adjacent the bead, and operating means by which the jaws are carried and operated.

2. An opener for a can having a bead, 10 comprising upper and lower jaws movable toward and from each other, the lower jaw including a plate engageable with the under edge of the bead, and a lateral projection engageable with the wall of the can to hold 15 said plate at a slight angle thereto, a blade on the other jaw to shear through the head of the can adjacent the bead, and handles operatively connected with the jaws.

3. An opener for a can having a bead, comprising upper and lower jaws movable toward and from each other, the lower jaw including a plate engageable with the under edge of the bead, a hook engageable over the bead, and a lateral projection engageable 25 with the wall of the can to hold said plate at a slight angle thereto, a blade on the other jaw to shear through the head of the can

adjacent the bead, and handles operatively connected with the jaws.

4. An opener for a can having a bead comprising upper and lower jaws movable toward and from each other, the lower jaw including a plate engageable with the under edge of the bead, the contacting edge of the plate being arcuate whereby it may roll on 30 the under edge of the bead, and a lateral projection engageable with the wall of the can to hold said plate at a slight angle thereto, a blade on the other jaw to shear through the head of the can adjacent the bead, and 35 handles operatively connected with the jaws.

5. An opener for a can having a bead, comprising upper and lower jaws movable toward and from each other, the lower jaw including a plate engageable with the under 40 edge of the bead, the contacting edge of the plate being arcuate to roll on the under edge of the bead, a blade on the other jaw to shear through the head of the can adjacent the bead, and handles operatively connected 45 with the jaws.

In testimony whereof, I have hereunto set my hand this 8th day of December, 1922.

JOHN A. LINN.
